UNITED STATES PATENT OFFICE.

VIRGIL C. BURGETT, OF LORAIN, OHIO.

TOOL.

Application filed September 10, 1927. Serial No. 218,844.

My invention relates to concrete molding and more particularly it relates to an improved tool for removing the spacer elements for the side walls of concrete molding forms.

5 An object of my invention is to provide a tool of length and weight sufficient to enable an operator to knock the spacer elements from a position between the side walls of the concrete form after the concrete has been poured 10 and set for a short period of time, and in which provision is made to facilitate ready withdrawal of the spacer elements from the form after they have been dislodged from engagement with the mold form side walls.

15 Another object of my invention resides in the provision of a tool of the class referred to which is durable, economical to produce and which may be readily handled efficiently.

20 These and other objects of my invention and the invention itself will become apparent from reference to the following description of an embodiment thereof and in which description reference will be had to the accompanying drawings forming a part of this 25 specification.

Referring to the drawings:

Fig. 1 is a perspective view of a section of a concrete molding form illustrating an embodiment of my invention in perspective and 30 depicting one mode of operation of the same;

Fig. 2 is a view partly in section and partly in elevation of an embodiment of my invention; and

Fig. 3 is an elevational view of the above 35 embodiment.

Referring to all the figures of the drawings in all of which like parts are designated by like reference characters, at 10, I show an elongated impact head preferably formed of 40 solid metallic material, such as steel and having a serrated impact striking surface 11 and a serrated side wall 12. A slot 13 is formed in the head intermediate the ends thereof, and the upper portion of the head is formed in 45 cylindrical shaped portion at 14, which portion is provided with a longitudinally extending threaded bore 15.

At 16, I show preferably an elongated 50 wooden handle for the tool, having an intermediate gripping portion and an enlarged end portion 17 to prevent the hands of the operator from slipping off the end of the same in use. The opposite end of the handle is threaded at 18, which is adapted to be screw- 55 threaded into the threaded bore 15 of the head to provide an adjustable connection between

the handle and the head to readily facilitate lengthening or shortening the tool as desired.

I preferably employ substantially J-shaped grapple jaw element 20, having a relatively long hook shaped portion 21 provided with a toothed gripping end 22, and a relatively short arm 23, disposed in the slot 13 of the head, with the arm 21 thereof projecting to one side of the head with its end 22 disposed adjacent the serrated portion 12 of the head, and with the other arm portion 23 projecting laterally of the opposite side of the head. A transverse bolt 25 extends across the slot onto which is pivoted the grapple 70 jaw element 20, the bolt being secured on the head spanning the slot, by virtue of a nut 26.

The outermost end of the relatively short arm 23 is provided with an eyelet 30 into which one end 31 of a long wire rod 32 is inserted and secured therein against accidental disengagement by twisting the same. This wire rod extends upwardly substantially parallel with the head and handle and is secured to the handle adjacent the upper end thereof. 80

A manually operable handle lever 35 comprising a hand grip portion 36, a laterally extending portion 37 pivoted at 38 to the handle adjacent the upper end thereof, and also being provided with an arm 39 having an eyelet 40 adjacent the end thereof into which is projected and secured by twisting it at 41 the upper end of the wire rod 32. A retractile coil spring 42 is provided for holding the handle lever in the position shown in 90 full lines in the drawings and having one end thereof secured in an eyelet 43, in the arm 39 adjacent the eyelet 40, and the opposite end thereof being fastened in an eye-bolt 44 secured to the handle 16 below the bolt 38. 95 The operating handle 35 is preferably formed of sheet metal and the handle portion 36 thereof, preferably rounded in its cross-sectional dimensions to enable the same to assume the position indicated in dotted lines 100 at 50, when it is swung on its pivot at which position a U-shaped sheet metal latch 51, pivoted at 52 adjacent the upper end of the handle 16, may be swung into the position illustrated in dotted lines at 53, to retain the handle portion 36 of the operating lever in substantial contiguous parallel relation with the handle 16. When so positioned the arm 39, spring 42, rod 32 and J-shaped grapple jaw lever 20 assume the respective positions indicated in dotted lines in Fig. 2 of the drawings. 110

The rod 32 may be provided with a turn

buckle 60 to facilitate adjustment thereof commensurate with the relative adjustment of the head 10 and handle 16. However, the rod may be made of wire material, which will enable it to be lengthened by straightening the twisted ends 31 and 41 thereof.

The use of the afore described tool, as best shown in Fig. 1, may be as follows:

Two by four uprights, such as 68 and 69 are commonly employed to brace side wall planks 70 and 71 of the usual concrete molding form, now in common use, these planks being secured together by virtue of a plurality of wires 73 twisted about each other and 10 projected through apertures in the planks and being looped at 74 about these uprights. Short wooden horizontally disposed spacer elements 75 are generally employed to hold the side walls apart by being jammed or 15 wedged between the side planks 70 and 71 of the form. It has heretofore been the practice to remove these spacer elements from the form after the concrete has been poured and partly settled, as shown at 80 in the 20 drawings, the concrete mass 81 having sufficiently hardened to permit removal of the 25 side planks of the form.

Great difficulty has heretofore been encountered in withdrawing these spacer elements after the concrete has been poured to a 30 depth wherein the spacer element 82 is partially imbedded therein. An operator desiring to withdraw spacer elements so imbedded after the concrete has settled sufficiently to render it partially self sustaining 35 in form together with the side wall planks of the mold, may strike an end of the spacer element 82 with sufficient force to dislodge it from a horizontal position wherein its ends 40 are wedged between the side wall planks of the form and when so dislodged, he may then grip the dislodged spacer element with the jaws 22 and 12 of the grapple by a pull on the handle 35, and then withdraw the tool and 45 spacer element from the form.

Having thus described my invention in a certain specific embodiment of my invention, I am aware that numerous and extensive departures may be made from the embodiment 50 herein illustrated and described without departing from the spirit of my invention.

I claim:

1. In a tool for removing the side wall spacer elements of a concrete molding form comprising an elongated metallic head having an impact striking surface adapted for striking the spacer elements to disengage it with the side walls of the form, a long handle for the head secured thereto at its non-striking end and extending in substantial alignment 55 therefrom, a substantially J-shaped grapple jaw element pivoted to the head at an intermediate portion of its longer arm and having the end of its shorter arm comprising a movable jaw projected to one side of the head,

and the end of its longer arm projected to the opposite side thereof, a jaw actuating spring retracting lever pivoted to the end of the handle remote from the head, said head presenting a roughened jaw surface on its head 70 towards the pivotal jaw, and a rod disposed along the side of the head adapted to communicate movement of the lever to the end of the grapple jaw element.

2. In a tool for removing the side wall spacer elements of a concrete molding form comprising an elongated metallic head having an impact striking surface adapted for striking the spacer elements to disengage it with the side walls of the form, a long handle for 75 the head adjustably secured thereto at its non-striking end and extending in substantial alignment therefrom to permit the tool to be lengthened, a substantially J-shaped grapple jaw element pivoted to the head at an intermediate portion of its longer arm and having the end of its shorter arm comprising a movable jaw projected to one side of the head, and the end of its longer arm projected to the opposite side thereof, a jaw actuating spring 80 retracting lever pivoted at the end of the handle remote from the head, said head presenting a roughened jaw surface on its head towards the pivotal jaw, and a rod disposed along the side of the head adapted to communicate movement of the lever to the end of the grapple jaw element.

3. In a tool for removing the side wall spacer elements of a concrete molding form comprising an elongated metallic head having 100 an impact striking surface adapted for striking the spacer elements to disengage it with the side walls of the form, a long handle for the head secured thereto at its non-striking end and extending in substantial alignment 105 therefrom, a jaw pivoted to the head, at an intermediate portion of its longer arm and having the end of its shorter arm comprising a movable jaw projected to one side of the head, and the end of its longer arm projected to the 110 opposite side thereof, a jaw actuating spring retracting lever pivoted to the end of the handle remote from the head, said head presenting a roughened jaw surface on its head towards the pivotal jaw, and a rod disposed along the side of the head adapted to communicate movement of the lever to the end of the grapple jaw element.

4. In a tool for removing the side wall spacer elements of a concrete molding form, 120 comprising an elongated metallic head having an impact striking surface adapted for striking the spacer element to disengage it with the side walls of the form, a long handle for the head, said head having a tubular internally threaded portion, said handle having an end thereof screw threaded into the head, and having a portion extending in substantial alignment therefrom, a jaw element pivoted 125 to the head at an intermediate portion of its 130

longer arm, and having the end of its shorter arm comprising a movable jaw projected to one side of the head and the end of its longer arm projected to the opposite side thereof, 5 a jaw actuating spring retracting lever pivoted at the end of the handle remote from the head, said head presenting a roughened jaw surface on its side opposite the movable jaw and a rod disposed along the side of the 10 head adapted to communicate movement of the lever to the end of the pivoted jaw.

5. In a tool for removing the side wall spacer elements of a concrete molding form comprising a solid metallic head having an impact serrated striking surface adapted for striking the spacer elements to disengage it with the side walls of the form, a long handle 15 for the head secured thereto at its non-strik-

ing end and extending in substantial alignment therefrom, a jaw pivoted to the head, 20 at an intermediate portion of its longer arm and having the end of its shorter arm comprising a movable jaw projected to one side of the head, and the end of its longer arm projected to the opposite side thereof, a jaw actuating 25 spring retracting lever pivoted to the end of the handle remote from the head, said head presenting a roughened jaw surface on its head towards the pivotal jaw, and a rod disposed along the side of the head adapted to 30 communicate movement of the lever to the end of the jaw.

In testimony whereof I hereunto affix my signature this 7th day of September, 1927.

VIRGIL C. BURGETT.
